H. A. HOOD.

CRUTCH.

APPLICATION FILED FEB. 27, 1908.

904,491.

Patented Nov. 17, 1908.

UNITED STATES PATENT OFFICE.

HARRY A. HOOD, OF SPENCER, MASSACHUSETTS, ASSIGNOR OF ONE-HALF TO CHARLES N. PROUTY, OF SPENCER, MASSACHUSETTS.

CRUTCH.

No. 904,481.

Specification of Letters Patent.

Patented Nov. 17, 1908.

Application filed February 27, 1908. Serial No. 418,143.

To all whom it may concern:

Be it known that I, HARRY A. HOOD, a citizen of the United States of America, and a resident of Spencer, in the county of Worcester and State of Massachusetts, have invented certain new and useful Improvements in Crutches, of which the following is a specification.

This invention relates to improvements in crutches, the object being to provide a crutch which may be adjusted to vary or change the distance between the arm-rest and the tip, as well as the distance between the handle or cross-piece and the arm-rest, so that a crutch made in accord with my invention may be adjusted to suit persons of different statures.

The invention consists in the construction of the lower portion of the crutch whereby it is provided with an adjustable lower end or tip-carrying member, such part having a bolt that engages with an internally threaded section which is rigidly secured to the lower end of the staff or body portion of the crutch, the adjustable end having mounted thereon a locking and incasing member or section whereby the parts may be held in rigid engagement, as will be hereinafter set forth.

The invention also consists in providing the side-bars of the crutch with longitudinal slots and corrugated reinforcing plates, and with a handle having internally threaded sockets with which engage right and left hand bolts, so that by turning the handle it may be released and then adjusted to and from the arm-rest.

The invention further consists in the particular construction and combination of the parts, as will hereinafter be set forth and particularly pointed out in the claims.

In the accompanying drawings, which form part of this specification, Figure 1 is a side elevation of a crutch made in accord with my invention. Fig. 2, is a front elevation, the lower portion of the crutch being in section. Fig. 3 is a vertical section of the lower portion of the crutch, showing the combined nut and sleeve out of engagement with the extension that is fixedly attached to the lower end of the body portion of the crutch. Fig. 4, is a detail view, which includes a side elevation and a section of the side bars of the crutch, the handle being in section. Fig. 5, is a front elevation of a

part of one of the side bars of the crutch, the handle being attached thereto, and Fig. 6, is a detail view of one of the bolts and its washer.

The staff or body portion A, of the crutch is of ordinary construction except that the side bars B, B thereof at a suitable distance below the arm-rest C, are provided with longitudinal slots D, D. The side-bars adjacent to the slots have attached thereto longitudinally slotted and transversely corrugated or ridged plates E, E, and on the inner sides of the side-bars are plain slotted plates F, F against which the ends of the handle G may impinge. The handle G, carries at each end internally threaded sockets H, H' to receive right and left handed threaded bolts I and I', each bolt having rectangular portions that enter the slots to hold the same against turning. The heads of the bolts may be corrugated on their inner faces, or they may be provided with washers having therethrough rectangular openings for the passage of the rectangular portions of the bolts. By the construction set forth and shown, when the handle G is turned in one direction the bolts will be drawn in to cause the heads or the washers to engage the plates E, and the sockets carried by the handle will bear against the inner side of the bars B, B, or against the plates F, F, and when the handle is turned in an opposite direction the bolts will be projected so that the handle may be moved to or from the arm-rest to change the distance between the handle and the arm-rest.

Below the junction of the side bars B, B of the body portion or staff A, there is a reinforcing band a through which is passed a rivet or pin b, that also passes through an eye in the upper end of a lag-screw or headless bolt K, which extends slightly below the lower end of the staff or body portion A, to engage an internally screw-threaded section L, and at the upper portion of such section there is a socket for the reception of the lower end of the wooden body portion or staff A. The lower end of the internally threaded section L is reduced to form a shoulder c against which a combined lock-nut and incasing sleeve M will abut to hold an extension member or extensible section N against movement. The extensible section of member N, is cylindrical in cross section and carries at its lower end a tip of

suitable construction, the bolt d being either integral or rigidly attached to the section N, such bolt also being slightly longer than the internally threaded portion of the section 5 L with which such bolt engages, so that the lower section N may be screwed into the section L until the same engages with the transverse wall of the locking and incasing member M. The locking and incasing member 10 M, is mounted upon the bolt which passes through an internally threaded aperture in said incasing member, and there is present a recess to receive the shouldered end of the fixed section L. The sleeve below its bolt 15 engaging portion is slightly longer than the larger part of the extensible section N, so that said part may entirely overlie such section when the bolt is screwed home to its full limit. When it is desired to extend or 20 shorten the crutch the section M is turned to bring the same out of engagement with the end of the internally threaded section L, and when this is done the section N may be turned to make the desired adjustment or 25 change in the length of the crutch.

It will be noted that the locking and incasing member of the crutch not only locks the extensible section by which it is carried, and covers that portion of the bolt which 30 would be exposed were it not for the sleeve, and that said sleeve serves as a brace for the extensible section, the internal diameter of the sleeve being substantially the same as the external diameter of the lower portion 35 of the extensible section.

I claim

1. An extendible crutch provided adjacent to the lower end of its staff or body portion with an internally screw-threaded member, 40 a tip-carrying member maintained in adjustable engagement therewith, and a combined locking and incasing member carried by the tip-carrying member.

2. An extendible crutch having adjacent 45 to its lower end an adjustable member for varying the length of the crutch, a member rigidly attached to the lower end of the staff or body portion of the crutch and constructed

so that the aforesaid adjustable member engages therewith, and means carried by the 50 adjustable member for holding the members in locked engagement one with the other.

3. An extendible crutch having at the lower end of its staff an internally threaded member, an end member provided with a 55 screw-threaded bolt for engagement with the internally threaded member, and a nut mounted on the threaded bolt, such nut having a sleeve that is adapted to receive a part of the bolt carrying member, substantially 60 as shown.

4. An extendible crutch that is provided at the lower end of its staff with a rigidly attached extension which is internally screw-threaded, an adjustable member from which 65 extends a screw-threaded bolt that engages with the rigidly attached extension, and an intermediate member comprising as a unitary part a nut and a sleeve which is mounted upon the bolt and is adapted to hold the 70 adjustable member in locked engagement with the rigidly attached member; the sleeve overlying a part of the adjustable member, substantially as shown.

5. A crutch provided with slotted side-bars, reinforcing plates having corresponding slots and corrugations adjacent to the side walls thereof, a handle having internally threaded sockets and bolts, the head of said bolts engaging the corrugated plates 80 when the threaded portions engage the sockets, substantially as shown.

6. In a crutch, side-bars having therethrough longitudinal slots, a handle having internally threaded sockets at each end, oppositely threaded bolts that engage the sockets, the bolts having rectangular portions that enter the slots and heads of greater width than the slots, substantially as shown.

In testimony whereof I affix my signature 90 in the presence of two witnesses.

HARRY A. HOOD.
